ATTORNEY

UNITED STATES PATENT OFFICE.

JOSEPH HREN, OF KINGSTON, NEW YORK.

TROUSERS-STRETCHER.

1,228,440.

Specification of Letters Patent. Patented June 5, 1917.

Application filed April 8, 1916. Serial No. 89,739.

To all whom it may concern:

Be it known that I, JOSEPH HREN, a citizen of the United States, and a resident of Kingston, in the county of Ulster and State of New York, have invented certain new and useful Improvements in Trouser-Stretchers, of which the following is a specification.

This invention relates to a trouser stretcher of novel construction, which may be introduced into a trouser leg and serves to effectively stretch and crease the same.

In the accompanying drawing:

Figure 1 is a side view of a trouser stretcher embodying my invention;

Fig. 2 a plan;

Fig. 3 a detail of the upper plate;

Fig. 4 a detail of the lower plate;

Fig. 5 a detail of the hook showing it closed;

Fig. 6 a detail of the hook showing it open;

Fig. 7 a detail end view of the joint showing it closed, and

Fig. 8 a front view thereof showing it open.

The trouser stretcher comprises essentially, a pair of flat longitudinal bars 1, adapted to engage the creases of a trouser leg. Each bar 1 is composed of an upper section, and a lower section, which may be removably secured to each other by means of a tongue 2 formed on the top of the lower section and engaging a pair of keepers 3 formed on the bottom of the upper section. In this way, the length of the stretcher may be halved, so that it may be readily packed into a trunk or suit case.

Near their upper ends there are pivoted to bars 1, at 4, the outer ends of a pair of upper links 5, the inner ends of which are pivoted at 6, to a common upper plate 7. This plate is furnished with a flange 8 having a pair of apertures 9 and 10, for a purpose hereinafter described. The pivoted inner ends of links 5, are enlarged to form rounded heads 11 that are provided with intermeshing teeth as shown.

Near their lower ends there are pivoted to bars 1, at 12, the outer ends of a pair of lower links 13, the inner ends of which are pivoted at 14 to a common lower plate 15.

This plate is furnished with a flange 16, having a single perforation 17. The inner ends of links 13 are likewise formed into toothed intermeshing heads 18.

To the top of each bar 1, there is pivoted at 19, a hook 20 adapted to engage the lower rim of a trouser leg 21. This hook is formed of resilient material, and comprises a doubled body carrying the pivot 19, and a correspondingly doubled beak 22 the body as well as the beak being adapted to straddle bar 1, and to obtain a firm hold on the trouser leg 21.

65

To lower plate 15, there is secured the lower knotted end of a string 23, that engages perforation 17. This string passes loosely through perforation 10 of plate 7, is doubled into a loop 24, and thence engages with its upper knotted end the perforation 9 of said last named plate.

In use, the device is introduced in a folded condition into the reversed trouser leg, the upper links 5 are spread, and the hooks 20 are closed upon the material 21. When now the device is suspended on a nail or similar holder 25, the weight of the trousers will cause a pull to be exerted upon string 23, whereby loop 24 will be lengthened, the lower end of the string to be drawn up, and the lower links 13 to be straightened out, so as to force the lower ends of bars 1 against the trouser leg with considerable pressure.

It will be seen that by the construction described, the movement of any one link will cause a corresponding movement of its mate, so that a uniform action is insured, and that the weight of the garment is utilized for effecting a constant pressure of the stretcher against the same.

I claim:

A trouser stretcher comprising a pair of longitudinal bars, an upper plate having an aperture, a lower plate, an upper pair of toothed intermeshing links pivoted to the bars and to the upper plate, a lower pair of toothed intermeshing links pivoted to the bars and to the lower plate, and a looped string secured to the plates at its ends, and passing loosely through the aperture of the upper plate.

JOSEPH HREN.
